Merchandise Kilgore*

UNITED STATES PATENT OFFICE

GUNNAR AHLQUIST, OF MINNEAPOLIS, MINNESOTA

CAN-OPENING DEVICE

Application filed December 8, 1928: Serial No. 324,611.

My invention relates to can opening devices and has for its object to improve the same as will hereinafter appear, and to this end it consists of the novel devices and combinations of devices hereinafter described and defined in the claims.

In the accompanying drawings, which illustrate the invention, like characters indicate like parts throughout the several views.

10 Referring to the drawings:

Fig. 1 is a top plan view of the device;

Fig. 2 is a section taken approximately on the line 2—2 of Fig. 1, some parts being shown in full;

15 Fig. 3 is a section taken on the line 3—3 of Fig. 2; showing the parts in an operative position; and

20 Fig. 4 is a section similar to Fig. 3, but showing the parts in an inoperative position with the cutting wheel drawn away from the feeding wheel for insertion over the rim of the can.

The device includes a mounting bracket 5 that is securable to any suitable support, but 25 which is shown as being secured to a table or counter top 6 by means of screws or the like 7. The mounting bracket 5 has an outwardly and upwardly inclined projection 8 in which, near the outer end thereof, is journaled a 30 shaft 9 that projects from a toothed or knurled rotary feeding wheel 10. Near the end of the shaft 9 opposite the feeding roller is a handle-equipped crank 11 that is removably secured thereto for movements there- 35 with by a screw 12 and a washer 13. The upper end of the shaft 9 to which the handle-equipped crank is applied is reduced to form a shoulder 14 between which and the washer 13, the end of the crank is pressed.

40 Journaled in the outwardly projecting portion 8 of the mounting bracket 5 inward of the shaft 9 is a stub shaft 15 of relatively large diameter which stub shaft is formed on one end of a lever 16. Projecting from the 45 under side of the stub shaft 15, eccentric to the axis thereof is a crank pin 17 on which is journaled a rotary cutting wheel 18. The rotary cutting wheel is held against axial movements by engagement on one side with the under side of the mounting bracket and

on the other side by engagement with a nut 19 on the outer end of the crank pin 17. The crank pin 17 is preferably reduced near its outer end to form a shoulder 20 against which the nut 19 is seated. The rotary cutting 55 wheel 18 includes a hub-like rim-engaging portion 18^a and a cutting edge 18^b that engages the cam just below its rim.

It is now apparent that when the operating lever 16 is turned from the position 60 shown by full lines in Figs. 1 and 2, the rotary cutting wheel will be caused to revolve around the axis of the stub shaft 15 and will be moved away from its normal operative position. When the parts are in their normal 65 positions, the cutting edge 18^b of the rotary cutting wheel slightly underlies the knurled or toothed edge of the feeding wheel 10.

Formed near the end of the lever 16 and surrounding but spaced from the stub shaft 70 15, is a cup-like flange 21, the free edge of which engages the top side of the outwardly projecting portion 8 of the mounting bracket 5. This cup-like flange 21 serves as a bearing 75 to hold the stub shaft and co-operating parts against downward movement and also encloses a spring 22 that is coiled around the stub shaft 15. One end of this spring 22 is inserted into a hole 23 in the lever 16 and the other end thereof is inserted into a hole 24 in 80 the mounting bracket. The said spring 22 acts to normally hold the lever 16, stub shaft 15, crank pin 17, and cutting wheel 18 in an operative position, as shown in Figs. 2 and 3, 85 but will allow the cutting wheel to be moved away from the feeding wheel by manual manipulation of the lever 16.

The device is illustrated as being applied to a can indicated by the numeral 25. The top of the can is indicated by the numeral 26, the rim by the numeral 27, and liquid contents therein by the letter *y*.

The device is operated as follows:

The lever 16 will be turned against the tension of the spring 22 from the position shown 95 by full lines in Figs. 1 and 2, to the positions shown by dotted lines in Fig. 1, in which position the cutting wheel 18 will be retracted to the position shown in Fig. 4. In this position of the parts, the rim 27 of the can may be 100

inserted between the feeding wheel 10 and the cutting wheel 18 and the lever 16 released. When the lever 16 is released the tension spring 22 will move the cutting wheel 18 toward the feeding wheel 10 so that its cutting edge 18^b will engage and be held under pressure of the spring 22 against the outside of the can just below the rim 27. The rim-engaging portion 18^a of the cutting wheel will now be slightly spaced from the rim of the can. By applying a slight hand pressure to the lever 16, the cutting edge 18^b of the cutting wheel will be inserted slightly through the side of the can and the rim-engaging portion 18^a of the cutting wheel will be moved into contact with the rim 27. The rim 27 of the can 25 will now be pressed between the knurled feeding wheel 10 and the rim-engaging portion 18^a of the cutting wheel 18 and when the handle-equipped crank is rotated, the rim 27 will be rolled between the feeding wheel and said rim-engaging portion of the cutting wheel. While the can is being thus rotated, it will, due to the angle at which the feeding and cutting wheels are disposed, remain in substantially vertical positions, so that the contents *y* thereof will not be spilled. When the can has been turned a complete revolution, the top thereof will be entirely severed from the main body of the can and the rim 27 may be readily released from its position between the wheels 10 and 18 by manipulation of the lever 16. After the can has been primarily punctured by manually forcing the cutting edge of the wheel 18 therethrough, the spring 22 will hold the cutting wheel 18 in an operative position through the balance of the complete cutting operation.

The angle at which the feeding wheel 10 and cutting wheel 18 are disposed is very important. These wheels 10 and 18 are disposed in a plane upwardly inclined from the horizontal corresponding to the incline of the outwardly and upwardly projecting portion 8 of the bracket 5. In practice, it has been found that a can being cut by an opener employing a rotary feeding wheel and a rotary cutting wheel will have a strong tendency to tilt at an angle to the plane in which said wheels are disposed and a great deal of difficulty has heretofore been experienced when openers of this general type have been rigidly secured to a support. In my device, however, the wheels are disposed at an angle to the horizontal and the can may remain in an upright position during the complete opening operation so that the contents thereof will not be spilled.

What I claim is:

1. In a can opening device, a mounting bracket securable to a support, a shaft journaled in said bracket, a feeding wheel mounted on one end of said shaft and operating means on the other end thereof, a lever having a stub shaft on one end that is journaled in

the bracket, a crank pin projecting from the free end of the stub shaft and eccentric to the axis thereof, a rotary cutting wheel journaled on said crank pin, said cutting wheel being movable about the axis of the stub shaft, when said lever is turned, to move the same toward and away from the rotary feeding wheel, and a spring for normally keeping the lever and cutting wheel in their operative positions.

2. In a can opening device, a mounting member, a rotary feeding wheel journaled to said mounting member, a lever means journaled to said mounting member, a rotary cutting wheel journaled to the journaled portion of said lever means eccentric to the axis thereof and movable toward and away from said feeding wheel when said lever means is manipulated, and resilient means normally tending to move said cutting wheel to its operative position.

In testimony whereof I affix my signature.

GUNNAR AHLQUIST.
